[57] **ABSTRACT**

An electrical terminal intended to be inserted into a flange of an electrical coil bobbin as a serrated mounting arm at one end, a U-shaped crimp portion at the other end and a laterally extending tab between the mounting arm and the crimp portion. The mounting arm is inserted into a hole in the bobbin flange, a wire from the coil is crimped to the terminal at the crimp portion, and the mounting arm is then bent towards the coil so that the tab extends parallel to the coil windings.

FIG. 1

FIG. 2

ELECTRICAL BOBBIN WITH TERMINALS**BACKGROUND OF THE INVENTION**

This application is a division of application Ser. No. 66,379 filed Aug. 24, 1970, now U.S. Pat. No. 3,641,650, hereby incorporated by reference.

FIG. 1 is a view of terminal strips

FIG. 2 is a view of an electrical bobbin with terminals.

The present invention is directed particularly to an electrical terminal 14 which may be manufactured in the form of a left and right hand strip 15, 15'. Each terminal has a mounting arm 16 which has serrated sides, a laterally extending tab 18 which is adapted to receive a receptacle type terminal, and a ferrule forming portion 20 extending from the tab and in alignment with the arm 16. The mounting arm is inserted into a hole 36 in a heavy section 12 of a flange 10 of a bobbin 4. A coil winding 34 is connected to the terminal by crimping a ferrule forming portion 20 and the arm 16 is then bent so that the terminal will extend parallel to the windings of the coil and will be located close to the bobbin 4. The terminal may be manufactured as a righthand strip or a lefthand strip as shown at 15, 15' so that the tabs 14, 14' will extend in opposite directions after assembly of terminals to a bobbin.

Further structural details of terminals in accordance with the invention and bobbin in terminal assemblies in accordance with the invention are set forth in the above identified U.S. Pat. No. 3,641,650. This patent also disclosed apparatus for inserting the terminal of the instant application into bobbins and simultaneously crimping the ferrule portions 20, 20' onto coil wires.

What is claimed is:

1. In combination with an electrical coil wound on a bobbin having a flange at least one end thereof an electrical connecting device, said connecting device having mounting means at one end thereof, said mounting means being secured to said flange, said connecting device extending inwardly of said bobbin and parallel to the axis thereof from said mounting means, said connecting device having tab means proximate to said mounting means for engagement with a complementary terminal means, and a crimped electrical connection between said connecting device and a conductor extending from said coil, said crimped connection extending from said terminal means and spaced from said coil.
